INVENTOR:

Soren C. Rockman.

UNITED STATES PATENT OFFICE.

SOREN C. ROCKMAN, OF PHILADELPHIA, PENNSYLVANIA.

SELF-HEATING GAS-IRON.

1,083,339.

Specification of Letters Patent.

Patented Jan. 6, 1914.

Application filed July 2, 1912. Serial No. 707,381.

To all whom it may concern:

Be it known that I, SOREN C. ROCKMAN, a citizen of the United States, residing at Philadelphia, in the county of Philadelphia and State of Pennsylvania, have invented certain new and useful Improvements in Self-Heating Gas-Irons, of which the following is a specification.

My invention relates to self-heating gas irons.

The object is to construct such sad iron with a hollow body, and so constructed that the bottom thereof will receive and take up substantially all the heat.

It also consists in adjustable means for confining the heat within the sad iron to the bottom and has means for preventing the escape of flames.

It further consists in certain improvements of construction whereby the heat within the body is fully transmitted to the bottom of the iron.

Figure 1 is a full side view. Fig. 2 is a rear-end view. Fig. 3 is a plan view with the cover removed. Fig. 4 is a sectional view at *a. a.* of Fig. 3. Fig. 5 represents a longitudinal section taken at the center of Fig. 3. Fig. 6 represents a section of the nipple secured in the burner tube.

Similar numerals refer to similar parts throughout the drawings.

In the drawings, 1 is a handle secured to a yoke 2, which is secured to a cover 3 by means of screws or bolts 4 and nuts 5. Screws 4 extend down and carry a deflector 6 by means of nuts 7, 7, so that the deflector can be adjusted up and down, whereby the space between it and the bottom part of the iron can be increased or decreased so as to allow for the escape of different quantities of gases. The deflector 6 is provided with a lining of asbestos 8 so as to prevent transmission of heat to the cover of the iron.

The deflector 6 is held by bolts 4 at an incline so as to afford the proper escape toward the exhaust exit 9 for the gases.

10 represents ribs extending across the iron and terminating close to the sides 11.

The central portion of the bottom of the iron at 12 is thin and forms between the thicker portions 13 and the ribs 10 pockets 14. The ribs 10 are connected by ribs 15 so as to abstract all the heat of the gases before escaping. The sides of the iron are cut at the top at 16 so as to allow the escape of gases above the deflector. 17 represents

holes for air inlets along the sides of the iron, which are located so as to let the air in, in the center of each pocket.

18 is a burner provided with gas exit holes 19, so located near the ribs 10 as to be within the pockets on each side of the air inlet holes 17 as shown on line *a. a.* of the burner.

The central rib 19' extends along the bottom, directly under the burner 18 so as to prevent the gases from escaping from one side to the other. The ribs 10 are drilled so as to admit the burner 18 which is held in place by a set screw 20.

The burner 18 is provided with a nipple 21 which is screwed into the said burner and by means of nut 22 can be adjusted so as to adjust the air inlet 23 to the burner.

24 is a gas regulating screw whereby the gas passes through the nipple, and can be decreased or increased for the quantity of gas required, or for the quantity or richness of gas used in the different localities.

To prevent the flame of the gas within the iron, from flashing back through opening 23, I provide a wire gauze or screen 24'.

25 is a wire-screen secured to deflector 6 and bent so as to cover exhaust outlet openings 9, thereby preventing escape of flames. Openings 16 in the sides of the iron may also be screened by wire as shown at 26.

27 are grooves adjacent to the ribs 10 which augment the heat absorbing surface so that all the heat generated in the combustion pockets or chambers 14 is quickly transmitted to the bottom of the sad-iron, so as to supply and maintain the bottom heat while operating, or ironing damp clothes. The ribs 10 and 15 on the thickened portion serve to abstract the remaining heat of the combustion before it escapes and will transmit such heat that is saved by these ribs and conducted downward to the bottom face of the iron.

The cover 3 is provided with a hook 3', which fits into a recess 2'.

28 is a hole or slot in the cover, and 29 is a handle intact with a set screw, fitting the threaded part 30 whereby the cover is held securely to the body of the iron.

Various changes may be made in the form and detail and arrangement of my invention without departing from the spirit thereof.

Having thus described my invention, I claim:

1. In a self-heating gas iron, a hollow

body, a cover therefor, a handle, a deflector or guide plate for guiding the exhaust gases rearward, bolts passing through the cover and handle, nuts on said bolts for securing 5 the handle to the cover, and nuts on said bolts for adjusting the height of either end and thereby the inclination of said guide plate.

2. In a self-heating gas iron, a hollow 10 body, a cover therefor, a handle, a deflector or guide plate for guiding the exhaust gases rearward, bolts passing through the cover and handle, nuts on said bolts for securing the handle to the cover, and nuts on said 15 bolts for adjusting the height and incline of said guide plate, an exhaust outlet in the wall of the iron, a screen secured to said plate, said screen extending upward to the top of the exhaust outlet and to the cover, 20 and down over the exhaust outlet for the purpose of preventing flames and hot combustion products from reaching the cover and escaping over the plate, and for preventing the flames escaping to the exhaust 25 outlet, from burning or scorching the material respectively, said screen being in one piece.

3. In a self-heating gas iron, a hollow 30 body, a cover therefor, an adjustable exhaust guide plate for directing the exhaust from the body, an exhaust outlet, a screen secured to said plate for preventing flames passing over the said plate and through the exhaust outlet respectively.

4. A self-heating sad iron having a hollow body, provided with a longitudinal depression and lateral air inlets, transverse heat absorbing and conducting ribs, longitudinal heat absorbing ribs integral with 40 said transverse ribs, recesses or grooves adjacent to the transverse ribs, a longitudinal bottom rib, holes in the transverse ribs, a burner passing through said holes, said transverse ribs and bottom rib dividing said 45 depression into combustion pockets or chambers, a removable cover for the said iron, an exhaust outlet, and an adjustable exhaust directing and heat retaining plate within the body.

5. A self-heating sad iron having a hollow body, provided with a longitudinal depression and lateral air inlets, transverse heat absorbing and conducting ribs, longitudinal heat absorbing ribs, integral with 55 said transverse ribs, recesses or grooves in the bottom adjacent to the transverse ribs, a lon-

itudinal bottom rib, holes in the transverse ribs, a burner for said iron located within the depression and passing through said holes, downwardly directed exit holes in 60 said burner, and said exit holes in the burner being staggered with the air inlets in the iron, said transverse ribs and bottom rib forming with the bottom and walls on the raised portion of the bottom, and sides 65 thereof, heat absorbing and conducting means, an adjustable heat entraining plate covering all ribs within the body for confining the heat to the ribs and to the bottom of the iron. 70

6. In a self-heating sad iron, a hollow body having its bottom provided with a central rib and side or lateral raised portions, transverse ribs integral with said raised portions and said central rib, said side portions 75 having grooves adjacent to the transverse ribs, holes in the transverse ribs, and a burner passing through said holes adjacent to said central rib.

7. In a self-heating gas iron, a hollow 80 body, the bottom of which has a central rib and side raised portions provided with grooves, adjacent to the central rib, ribs integral with said side portions, adjacent to the outer walls of the iron; heat absorbing 85 and conducting ribs integral with the raised portions and the side ribs and an adjustable deflector extending over said raised portions and over all the ribs for the purpose of retaining the heat and confining the heat between 90 said ribs and to the bottom of the iron.

8. In a self-heating gas iron, a hollow body having a bottom with a central rib and with grooved raised side portions, said 95 grooved side portions being thicker than the central rib, a burner centrally located and substantially below the top of said grooved side portions.

9. In a self-heating gas iron, a hollow 100 body, having a bottom with a central rib and also laterally grooved side portions, a burner centrally located and substantially below the top of the said grooved side portions. 105

In testimony whereof I affix my signature in presence of two witnesses.

SOREN C. ROCKMAN.
